H. T. BARNWELL

CURTAIN ROD BRACKET

Filed March 21, 1921

Fig. 1.

Fig. 2.

Inventor:

Harry T. Barnwell

By Counselor, Bryant & Darby
Atty's.

UNITED STATES PATENT OFFICE.

HARRY T. BARNWELL, OF OGDENSBURG, NEW YORK, ASSIGNOR TO THE NEWELL MFG. CO. INC., OF OGDENSBURG, NEW YORK, A CORPORATION OF MAINE.

DESIGN FOR A CURTAIN-ROD BRACKET.

Application filed March 21, 1921. Serial No. 454,292. Term of patent 14 years.

To all whom it may concern:

Be it known that I, HARRY T. BARNWELL, a citizen of the United States, residing at Ogdensburg, county of St. Lawrence, State of New York, have invented a new, original, and ornamental Design for Curtain-Rod Brackets, of which the following is a specification, reference being had to the accompanying drawing, forming a part thereof.

Fig. 1 is a front elevational view showing

my new and ornamental design, and Fig. 2 is a side elevational view of the bracket shown in Fig. 1.

I claim:

The ornamental design for a curtain rod bracket as shown.

HARRY T. BARNWELL.
